S. L. G. KNOX

SUBMARINE CONSTRUCTION

Filed May 9, 1922

Patented July 8, 1924.

1,500,997

UNITED STATES PATENT OFFICE.

SAMUEL LIPPINCOTT GRISWOLD KNOX, OF NEW YORK, N. Y.

SUBMARINE CONSTRUCTION.

Application filed May 9, 1922. Serial No. 559,512.

To all whom it may concern:

Be it known that I, SAMUEL LIPPINCOTT GRISWOLD KNOX, a citizen of the United States, residing at New York, in the county 5 of New York, State of New York, have invented certain new and useful Improvements in Submarine Construction; and I do hereby declare the following to be a full, clear, and exact description of the invention, such as will enable others skilled in the art to which it appertains to make and use the same.

During the latter part of the World War a new method for detecting submarines was 15 developed, involving the use of so-called supersonic waves. These are high frequency vibrations in a material medium, the range employed for detections varying from 20,000 to 200,000 per second. In accordance with this method such waves are projected from a searching ship or station, strike the submarine, and come back as echoes to the apparatus sending them forth. Special devices transform these supersonic 25 waves into waves of a different frequency, so that they become audible to a properly equipped listener in the searching ship or station. Unlike the lower frequency and audible sound wave, the supersonic wave 30 does not spread equally in all directions, but acts more like light, proceeding in a narrowly defined path, and being reflected from the submarine in much the same way that light is reflected from a mirror.

It is the object of the present invention to provide means which shall enable the submarine to escape detection by these supersonic waves, or at least to lessen the chances of detection by such waves. To 35 this end I propose shaping those parts of the submarine that would tend to reflect the wave back to the searching ship or station so that it is not reflected back. Since the supersonic wave is reflected back to the ship or station by those parts of the submarine which are vertical, or nearly vertical, unless very close to the ship or station, elimination 40 from the submarine of most all vertical, or substantially vertical, surfaces and properly screening, as far as practicable, such other vertical surfaces as cannot themselves be changed, would greatly lessen the danger 45 of detection by supersonic waves. More specifically, the sides of the conning tower, the sides of the hull, the sides of the ballast tanks and any other exposed areas are made

to slope away from the vertical so as to reflect the incident waves upwardly or downwardly. Such surfaces as cannot themselves be changed, such as the rudder, are protected by a sloping shell or screen. The 50 object of the invention can be attained by thus constructing the hull of the vessel itself, but in many cases it may not be practicable nor desirable to do this, and the same 55 result can be obtained by providing the vessel with a properly shaped shell which will reflect the supersonic waves so that they will not return to the sending station, and without materially affecting the structure 60 of the vessel itself.

While the invention is not restricted to any particular construction, there has been 65 illustrated in the accompanying drawings, in a diagrammatic way, the structural idea 70 of the invention.

Referring to these drawings, Fig. 1 is a side view of a submarine, constructed in accordance with this invention; Figs. 2, 3, 4 and 5 are sections taken respectively on the lines 2—2, 3—3, 4—4, 5—5; Fig. 6 is 80 a view of the rear end of the submarine, and Figs. 7 and 8 are sectional views somewhat similar to Figs. 2 and 3 respectively, showing a modified construction. 85

The pressure resisting hull of the submarine is indicated at 5 and with it is associated the usual ballast tanks 6, storage battery compartment 7, conning tower 8, torpedo tubes 9, deck 10, periscope 11, propellers 12 and rudder 13. Arranged over certain of the mentioned parts of the submarine is a shell comprising sloping portions 14 and 15, which are sloped sharply away from the vertical and which are 90 designed to reflect the supersonic wave sharply upwardly to the surface or downwardly to the bottom. The sides of the conning tower as indicated at 16 and 17 are similarly sloped. The fore self-bailing 95 and self-filling compartment 19 and the aft self-bailing and self-filling compartment 21 are similarly sloped as shown in Figs. 4 and 5. It is evident that the sloping part 14 of the reflecting shell may be made practically continuous with the walls of the self-bailing and self-filling compartments 19 and 21. 100

Referring to Fig. 6, a reflecting screen or shield 21' is arranged over the propellers 110 and rudders for screening them from the supersonic waves. Since the rudder is usu-

ally vertical, it is, of course, important that it be screened effectively. The screen 21' is placed to permit ready access of the water to the propellers and rudders; to this end, the angle between the sides of the screen 21' is made slightly greater than the angle between the sides of the screen 21, thus providing a space 22 between the two screens into which water may enter and pass to the propellers and rudder.

The submarine thus far described embodies three shells, the pressure resisting shell, the ballast tank shell, and the shell for reflecting the supersonic wave. However, only two shells need be used if desired, and such a construction is illustrated diagrammatically in Figs. 7 and 8. In these figures, instead of a third reflecting shell being placed over the ballast tank, the ballast tank itself is shaped on the outside so as to reflect the supersonic wave sharply upwardly or downwardly.

Thus a shell 31 is arranged around the pressure resisting hull 5 of the submarine; partitions 32 serve to brace this shell from the hull 5 and to define a ballast tank 33, below certain of such partitions. In this modification the conning tower is sloped as in Fig. 2, and, of course, the rudder and propellers are screened as in Fig. 6.

While supersonic waves have been discussed in connection with the invention, it should be understood that the invention in its broader aspect consists in so shaping the submarine as to deflect any water-transmitted wave, supersonic or otherwise, and so as to reflect as little as possible of the wave back to the watching ship or station. Although the invention has been illustrated in connection with a mobile underwater structure, it is also applicable to a stationary underwater structure, such as a submarine mine.

It is not claimed that a submarine may be absolutely screened from detection by this method, for when it is so close to the watching ship or station as to bring it within the effective range of the secondary, tertiary, etc., waves of the supersonic apparatus, the chances of detection will be greatly increased, for then secondary, tertiary, etc., waves embrace a much greater total angle with respect to the sending source than the

long, primary wave, and conversely, the receiving apparatus may detect the relatively weak waves reflected from the submarine in directions not normal to the surface thereof. But it is believed that the system proposed will reduce by 75 per cent or more the range within which a submarine is subject to detection by supersonic waves, as compared with one so built as to present normal, or approximately normal surfaces—even though of very small area—to the primary wave issuing from the supersonic apparatus.

I claim:

1. A submarine, the external surfaces of which make an angle with the vertical so as to reflect upwardly or downwardly supersonic waves striking them from the side.

2. A submarine designed to escape detection by supersonic or detecting waves, the parts of which that are able to reflect the wave being made sloping with respect to the vertical, for reflecting the wave upwardly or downwardly to the surface or downwardly to the bottom.

3. A submarine designed to escape detection by supersonic or detecting waves, comprising a pressure-resisting hull, and a shell associated with the hull having external surfaces sloping with respect to the vertical for reflecting the wave upwardly or downwardly.

4. A submarine designed to deflect supersonic or detecting waves so that they will not be reflected back to their point of origin, in which substantially all the external portions of the submarine are at an angle to the vertical, so that the waves are reflected upwardly to the surface or downwardly toward the bottom.

5. A submarine, designed to escape detection by supersonic waves sent out by a ship or station, provided with external surfaces sloping away from the vertical, and with screens, sloping away from the vertical over certain parts of the submarine, the said sloping external surfaces and the said sloping screens serving to reflect the detecting waves upwardly to the surface or downwardly to the bottom, rather than back to the ship or station.

In testimony whereof I affix my signature.

SAMUEL LIPPINCOTT GRISWOLD KNOX.
